US00D794072S

(12) United States Design Patent (10) Patent No.: US D794,072 S
(45) Date of Patent: * Aug. 8, 2017

(54) PORTION OF A DISPLAY SCREEN WITH ICON

(71) Applicant: RUBICON GLOBAL HOLDINGS, LLC, Atlanta, GA (US)

(72) Inventors: Mircea Dragoi, Târgu-Mureş (RO); Stefan Balan, Veresti (RO)

(73) Assignee: RUBICON GLOBAL HOLDINGS, LLC, Atlanta, GA (US)

() Term: 15 Years

(21) Appl. No.: 29/562,727

(22) Filed: Apr. 28, 2016

(51) LOC (10) Cl. 14-04

(52) U.S. Cl.

USPC D14/492

(58) Field of Classification Search

USPC D14/485-495

CPC . G06F 3/0481; G06F 3/04817; G08G 1/0962;

G08F 1/123
